UNITED STATES PATENT OFFICE.

ARNOT K. DEVOE, OF BOSTON, MASSACHUSETTS.

FILING-SPINDLE.

SPECIFICATION forming part of Letters Patent No. 678,721, dated July 16, 1901.

Application filed April 19, 1901. Serial No. 56,602. (No model.)

To all whom it may concern:

Be it known that I, ARNOT K. DEVOE, of Boston, in the county of Suffolk and State of Massachusetts, have invented certain new and 5 useful Improvements in Paper-Files, of which the following is a specification.

This invention relates to paper-files for desk use for the purpose of temporarily filing or retaining papers, and is intended as a substitute for the ordinary pointed spindle which is held in a vertical position by a supporting foot and on which the papers to be retained are impaled.

The invention has for its object to provide 15 a filing device which shall retain the papers without perforating them, thus avoiding the injury or mutilation which would attend the use of a perforating or impaling spindle.

The invention consists in the improvements 20 which I will now proceed to describe and claim.

Of the drawings, Figure 1 is a side elevation of a paper-file embodying my invention. Fig. 2 is a section on line 2 2, Fig. 1. Fig. 3 25 is a view similar to Fig. 1, showing the telescopic standard of the device contracted to separate the two paper clamping or grasping parts. Fig. 4 represents a view similar to Fig. 1, showing a somewhat different form of 30 stop-arm coöperating with the telescopic standard and its head. Fig. 5 represents a top plan view of my improved spindle.

The same characters of reference indicate 35 similar parts or features in all the drawings. In the drawings, *a* represents a foot, which is preferably of circular form and adapted to rest upon a desk or table.

b *b'* are the parts or members of a telescopic standard supported by the foot and extending 40 vertically from the central portion thereof, the part *b* being tubular and affixed rigidly to the foot, while the part *b'* is movable in the part *b* toward and from the foot.

c represents a paper-clamping head affixed 45 to the upper end of the part *b'* of the standard and preferably made in the form of a substantially circular flat plate, the diameter of which may be substantially the same or somewhat less than that of the foot *a*.

50 *d* represents a standard-extending spring which is interposed between the foot *a* and the head *c* and normally extends the stand-

ard and raises the head *c* as far as the stop-arm next described will permit.

e represents a stop-arm which is affixed to 55 and projects upwardly from the foot *a* and is bent at its upper end to form a stop-finger or clamp *e'*, which projects over the head *c* and limits the upward movement of the latter by the spring *d*.

The stop-arm *e* is preferably composed of a piece of wire, the central portion 2 of which constitutes the acting portion of the finger *e'*, while the end portions 3 3 connect said finger with the foot *a*. The portions 3 3 preferably 65 pass through orifices 4 4, formed in the head *c*, and are guided by said orifices, said orifices acting as guides, whereby rotary movement of the head is prevented. In Figs. 1, 2, and 3 I show the portions 3 coiled near their lower 70 ends to form spring convolutions 6, which permit the arm 3 as a whole to swing back and forth between the positions indicated in Figs. 1 and 3, the portions 3 being curved, so that when the head is depressed it will swing the 75 arm outwardly, as shown in Fig. 3, and when the head is raised it will return the arm to the position shown in Fig. 1. In Fig. 4 the portions 3 of the arm are vertically arranged and are not caused to swing by the movement 80 of the head.

It will be seen that when it is desired to file papers the paper to be filed is pressed downwardly upon the head *c*, thus separating the latter from the finger *e'*, so that the paper can 85 be interposed between said finger and the head. When the head is released, it is raised by the spring, and the paper is clamped between the head *c* and finger *e'*.

It will be seen that this improved device is 90 compact and occupies but little space and is adapted to hold an accumulation of papers without perforating or injuring the same.

I claim—

1. A paper-file comprising a foot, a stop-arm projecting upwardly from the foot and bent at its upper portion to form a clamping-finger or stop, and a vertical telescopic standard supported by the foot and having an extending-spring, and a head at the upper end 95 of the standard which is pressed yieldingly against said finger by the standard-extending spring, said standard serving to guide the head in its vertical movements.

2. A paper-file comprising a foot, a cylindrical vertical telescopic standard supported thereby and having a head at its upper end, a spring coiled about said standard and normally pressing said head upward, and a stop-
5 arm projecting upwardly from the foot and through guides in the head whereby rotary movement of the head is prevented, said stop-

arm having an upper portion extending over the head to coact therewith as a clamp.

In testimony whereof I have affixed my signature in presence of two witnesses.

ARNOT K. DEVOE.
